[57] **CLAIM**

The ornamental design for a dispenser for air treating material, as shown and described.

DESCRIPTION

FIG. 1 is a perspective view of a dispenser for air treating material showing my new design;

FIG. 2 is a top plan view thereof;

FIG. 3 is an elevational view taken from one side thereof, the opposite side being the same as the side shown;

FIG. 4 is an elevational view taken from one end thereof, the opposite end being the same as the end shown; and

FIG. 5 is a bottom plan view thereof.

FIG. 1

FIG. 2

FIG. 3

FIG. 4

FIG. 5
